UNITED STATES PATENT OFFICE.

THOMAS R. McKNIGHT, OF AURORA, ILLINOIS, ASSIGNOR TO WESTERN WHEELED SCRAPER COMPANY, OF AURORA, ILLINOIS, A CORPORATION OF ILLINOIS.

GRADING-MACHINE.

1,265,098.

Specification of Letters Patent. Patented May 7, 1918.

Application filed July 20, 1914. Serial No. 852,010.

To all whom it may concern:

Be it known that I, THOMAS R. McKNIGHT, a citizen of the United States, residing at Aurora, in the county of Kane and State of Illinois, have invented certain new and useful Improvements in Grading-Machines, of which the following is a specification, reference being had to the accompanying drawings.

10 My invention relates to grading machines and it has for its object to improve the construction of the steering devices for the front wheels of the carriage and the devices for extending and adjusting the position of 15 the rear wheels, so that the machine may be easily and efficiently handled under the varying conditions attending its operation. I accomplish this object as illustrated in the drawings and as hereinafter described. That 20 which I believe to be new is set forth in the claims.

In the drawings,

Figure 1 is a side elevation of my improved grading machine;

25 Fig. 2 is a plan view thereof, the dotted lines indicating the extended position of the members of the rear axle;

Fig. 3 is a plan view of the rear axle and 30 wheels, showing the devices for adjusting the same;

Fig. 4 is a cross-section on line 4—4 of Fig. 3; and

Fig. 5 is a cross-section on line 5—5 of Fig. 3.

35 Referring to the drawings, in which I have illustrated my improvements as applied to a grading machine of the type shown and described in my pending application, Serial No. 33,026, filed June 9, 1915,

40 in which the scraper-blade is arranged to be moved endwise upon its support—

10—11 indicate the side-bars of the main frame of the carriage, which are preferably Z-shape in cross-section. Said side-bars are 45 spaced a suitable distance apart and are connected by braces so as to make a strong, rigid frame. The end portions of said bars are curved downward, as shown in Fig. 1, so that the intermediate portion of the carriage frame is higher than the end portions 50 thereof, as shown. 12 indicates the front wheels, which are mounted upon spindles carried by a front axle 13, which is connected in any suitable way, as by a bolster

14, with the lower member 15 of a fifth wheel. 16 indicates a draft-bar connected with the front axle, and 17 indicates the tongue which is connected to a strap 18 which is pivoted at 19 to the draft-bar 16. 20 indicates a curved rack-bar having teeth 60 on its concave side, which extends across the tongue 17, preferably at the under side thereof, and is connected at its ends with forwardly-extending bars 21—22 connected with the end portions of the axle 13, as 65 shown in Fig. 2. 23 indicates a bracket secured to the under side of the tongue 17 and extending under the rack-bar 20 for supporting the same. The rack-bar 20 is adapted to swing to one side or the other to 70 turn the front axle 13 and thus steer the machine. For the purpose of swinging said rack-bar, I provide a shaft 24 vertically mounted at the rear end portion of the tongue, as shown in Fig. 2, said shaft carrying 75 a pinion 25 which meshes with the teeth of the rack-bar 20. 26 indicates a worm-wheel, also carried by the shaft 24 which meshes with a worm 27 journaled in suitable bearings in a bracket 28 mounted 80 upon the upper side of the tongue, said bracket also being provided with a bearing for the upper part of the shaft 24. The worm 27 is rotated by a hand-wheel 30 conveniently disposed on the intermediate portion 85 of the carriage frame, upon the rear end of a shaft 31 which is mounted in suitable bearings, as 32—33, and is connected by a universal joint 34, shaft 35, and universal joint 36 with the worm 27. Thus by rotating the hand-wheel 30 the rack-bar 20 may 90 be moved in either direction to steer the machine in the desired direction.

The rear axle of the machine is composed of two parallel members 37—38 which, in 95 the construction illustrated, are square in cross-section and are fitted in a rectangular frame 39 which holds them in contact with each other. One end of said frame 39 is mounted on a vertical pivot 40 which is fitted in a box-like bracket 41 secured to one of the side-bars of the carriage, as 11, the arrangement being such as to permit the opposite end of the frame 39 to swing forward and backward about the pivot 40 as an axis. 100 The opposite end of said frame 39 extends into another box-like bracket 42 which is secured to the other side-bar 10 of the car-

riage and is provided on its under surface with a slightly curved rack-bar 43, as best shown in Fig. 4. At this end of the frame 39 there is provided a shaft 44 carrying a pinion 45 which meshes with the rack-bar 43, and a worm-wheel 46 which meshes with a worm 47 carried at the lower end of a rod 48 fitted in a bearing 49 provided at one side of the frame 39, as shown in Fig. 4. The 10 rod 48 has a hand-wheel 50 at its upper end for rotating it, as shown in Fig. 2. By this construction by rotating the hand-wheel 50 the right-hand end of the axle frame 39 may be swung forward or backward, thereby 15 changing the angular relation of the members of the rear axle to the line of draft. The members of the rear axle are provided with racks at one side, as shown in dotted lines at 51—52 in Fig. 3, the rack 51 being 20 arranged to mesh with a pinion 53 carried at the lower end of a rod 54, and the rack 52 meshing with a pinion 55 carried at the lower end of a rod 56. 57—58 indicate hand-wheels at the upper ends of the rods 25 54—56, respectively, as shown in Fig. 2. Thus by means of these hand-wheels either member of the rear axle may be projected or retracted independently of the other and also independently of the angular relation 30 of the rear axle as a whole to the line of draft. 59—60 indicate the rear wheels, which are mounted, respectively, upon the axle members 37—38, as shown in Fig. 3. 61 indicates a platform provided for the 35 operator at the rear end of the machine, as shown in Fig. 1. As shown in Fig. 1, the forward ends of the side-bars 10—11 are connected by a bracket 62 with the upper member 63 of the fifth wheel.

40 From the foregoing description it will be apparent that the front wheels are steered when in operation by means of the hand-wheel 30 and that the rear axle may also be swung about the pivot 40, by operating the hand-wheel 50, to steer the rear portion 45 of the machine in either direction. Thus the machine may be very accurately and quickly guided along any desired path. When desired, either of the rear wheels may 50 be extended by operating the hand-wheels 57—58.

55 The construction shown and described for mounting and adjusting the scraper-blade is not herein claimed, as it forms the subject-matter of my pending application hereinbefore referred to.

60 It will be understood that my invention is not restricted to the specific details of the construction shown and described, except in so far as they are particularly claimed, as my invention includes generically the subject-matter of the broader claims.

65 That which I claim as my invention, and desire to secure by Letters Patent, is,—

1. In a grading machine, the combination

of a frame, a rear axle pivotally connected with said frame to swing about a vertical axis, the pivot of said axle being adjacent to one side of the frame, wheels mounted on the end portions of said axle, and means 70 for swinging said axle horizontally about said pivot to simultaneously adjust said wheels angularly.

2. In a grading machine, the combination 75 of a frame, a rear axle pivotally connected with said frame to swing about a vertical axis, the pivot of said axle being adjacent to one side of the frame, wheels mounted on the end portions of said axle, and rack and pinion mechanism for swinging said 80 axle horizontally about said pivot to simultaneously adjust said wheels angularly.

3. In a grading machine, the combination 85 of a frame, a rear axle pivotally connected with said frame adjacent to one side thereof and adapted to swing horizontally, a rack connected to the frame adjacent the opposite side thereof, a pinion carried by the axle and meshing with said rack, a rod mounted on the axle and having a worm 90 and worm-wheel for rotating said pinion, and a hand-wheel for rotating said rod.

4. In a grading machine, the combination 95 of a frame, a rear axle pivotally connected with said frame to swing about a vertical pivot, said axle being composed of extensible members, the pivot of said axle being adjacent to one side of the frame, and means for swinging said axle horizontally about 100 said pivot.

5. In a grading machine, the combination 105 of a frame, a rear axle pivotally connected with said frame to swing about a vertical axis, said axle being composed of extensible members, the pivot of said axle being adjacent to one side of the frame, and rack and pinion mechanism for swinging said 110 axle horizontally about said pivot.

6. In a grading machine, the combination 110 of a frame, a rear axle pivotally connected with said frame adjacent to one side thereof and adapted to swing horizontally, said axle being composed of extensible members, a rack connected to the frame adjacent the opposite side thereof, a pinion carried by 115 the axle and meshing with said rack, a rod mounted on the axle and having a worm and worm-wheel for rotating said pinion, and a hand-wheel for rotating said rod.

7. In a grading machine, the combination 120 of a frame, a rear axle pivotally connected with said frame to swing about a vertical axis, the pivot of said axle being adjacent to one side of the frame, wheels mounted on the end portions of said axle, means for swinging said axle horizontally about said pivot to simultaneously adjust said wheels angularly, front wheels supporting the forward portion of said frame, and means for steering said front wheels. 125

8. In a grading machine, the combination of a frame, a rear axle pivotally connected with said frame to swing about a vertical pivot, said axle being composed of extensible members, the pivot of said axle being adjacent to one side of the frame, means for swinging said axle horizontally about

said pivot, front wheels supporting the forward portion of said frame, and means for steering said front wheels.
